UNITED STATES PATENT OFFICE.

GEORGE C. CHEEK, OF SACRAMENTO, CALIFORNIA, ASSIGNOR OF ONE-SIXTH TO OMER E. CHEEK AND ONE-SIXTH TO RODNEY J. MORRISSEY, BOTH OF SACRAMENTO, CALIFORNIA.

DIRECTION-INDICATOR.

1,276,873.

Specification of Letters Patent. Patented Aug. 27, 1918.

Application filed October 8, 1917. Serial No. 195,439.

To all whom it may concern:

Be it known that I, GEORGE C. CHEEK, a citizen of the United States, residing at Sacramento, in the county of Sacramento and State of California, have invented new and useful Improvements in Direction-Indicators, of which the following is a specification.

This invention relates to a direction indicator.

One of the objects of the present invention is to provide a simple, compact, cheaply manufactured device of the character described, which may be stationed at railway crossings as a danger signal, used by traffic officers at street crossings to display traffic signals or directions, and used for advertising and other purposes, but particularly as a direction indicator for automobiles by showing words, such as "Right," "Left" or other suitable signals which will indicate the intended movements of the automobile. Another object of the invention is to provide a simple electrical control, whereby the mechanism may be readily operated by the driver. Further objects will hereinafter appear.

The invention consists of the parts and the construction and combination of parts as hereinafter more fully described and claimed, having reference to the accompanying drawings, in which—

Figure 1 is a front view of the direction indicator.

Fig. 2 is a central, vertical cross section of same.

Fig. 3 is a view of the wiring diagram.

Referring to the drawings in detail, A indicates a casing constructed of sheet iron or any other suitable material, which, in the present instance, is divided into four separate compartments, such as shown at 2, 3, 4 and 5, by a horizontal partition plate 6 and a vertical partition plate 7. Formed on each side of the casing are guideways 8 which are provided for the reception of removable slides 9, one for each side of the casing. These slides are constructed of glass, celluloid or any other suitable transparent or semi-transparent material, and the glass or material provided is preferably mounted in a frame 10 which fits the guideways 8.

Painted on the interior surface of the 55 plates 9 are the words "Right" and "Left"; the word "Left" registering with the upper compartments 2 and 3 and the word "Right" with the lower compartments 4 and 5. Mounted between the compartments 2 and 60 3 is an electric light 11, and mounted between the compartments 4 and 5 is an electric light 12, the center partition plate 7 being cut away to permit the insertion of the lights, thus permitting one light to illuminate two compartments simultaneously. The lamp 11 illuminates compartments 2 and 3 while the lamp 12 illuminates the compartments 4 and 5.

There are two removable plates 9 held by 70 the guideways, one on each side of the casing, and as each plate is provided with the words "Right" and "Left", illumination of the upper compartment will display the word "Left" so that it may be seen by 75 pedestrians and drivers of vehicles both from the front and the rear, the same display being accomplished when the lower compartments are illuminated.

The lights may be furnished with current 80 from any suitable source or a battery, such as shown at 13, and the circuit to the lights may be controlled by any suitable form of switch, such as shown at 14, positioned within convenient reach of the driver of the automobile. While one direction indicator has been found sufficient, it is obvious that two may be employed one on each side of the car, and while the device has been described as employed in connection with automobiles it 85 may also be used by traffic officers or placed at railway crossings as a danger signal and may also be used for advertising and other purposes in general.

One important feature of the present invention is the fact that the directing words or other matter contained are only displayed when the electric lights are operated, this being true whether in the daytime or at night. The interior of the casing is perfectly dark and as the words, for instance "Right" and "Left", are painted on the interior side of the glass plates and as these plates are ground or otherwise rendered semi-transparent, it can readily be seen that 100 the words will not be displayed except when illuminated from the rear. The vertical

partition 7 prevents light from passing through the glass plates 9, and thus prevents the legends from being visible during the day. The same result may be obtained by printing the words backward on a sheet of paper and placing the same between the glass plates and the compartments, as shown at 17, the semi-transparent effect being obtained by the paper, clear glass or other material being employed in that instance.

The plates are held in the guideways by one or more swinging lugs, such as shown at 15. These lugs are pivotally attached to the casing, as shown at 16, and when swung 15 crosswise thereof, as shown in Figs. 1 and 2, they will engage the undersides of the plates 9 and support the same against accidental removal. If it is desired to remove the plates to change the display, or for any 20 other purpose, it is only necessary to swing the lugs 15 out of engagement with the plates, thus permitting the same to be quickly and readily removed.

The materials and finish of the device as 25 a whole may otherwise be such as the experience and judgment of the manufacturer may dictate.

It should also be understood that the casings may be supported upon brackets or any 30 suitable means, and I also wish it understood that various changes in form, proportions and minor details of construction may be restored to within the scope of the appended claims and that I do not wish to 35 limit myself to the specific design and construction here shown.

Having thus described my invention, what

I claim and desire to secure by Letters Patent is—

1. In a direction indicator, a casing, a horizontal partition in the casing forming an upper and a lower compartment, a vertical partition in the casing bisecting the horizontal partition and forming a pair of upper and a pair of lower compartments, a semi-transparent legend bearing plate for each side of the casing, said vertical partition acting to prevent light from passing through the casing from one plate to the other and said vertical partition having an opening 50 above and an opening below said horizontal partition, and an electric lamp in each opening extending on opposite sides of the vertical partition so as to simultaneously illuminate the respective pairs of upper and lower compartments.

2. In a direction indicator, a casing, a pair of vertical guide ways on each side of the casing, glass plates having legends associated therewith slidably in said respective pairs of guide ways, and members pivoted between their ends to the bottom of the casing and having their said ends engageable with and beneath the respective glass plates to hold the latter against down movement, whereby the swinging of each member will simultaneously release both glass plates.

In testimony whereof I have hereunto set my hand in the presence of two subscribing witnesses.

GEORGE C. CHEEK.
